Primary Examiner — Karen S Acker*Assistant Examiner* — Jasmine Mlinarcik(74) *Attorney, Agent, or Firm* — Edell, Shapiro & Finn, LLC**CLAIM**

The ornamental design for a cap, as shown and described.

DESCRIPTION

FIG. 1 is a front perspective view of a cap showing our new design;

FIG. 2 is a rear perspective view thereof;

FIG. 3 is a front view in elevation thereof;

FIG. 4 is a rear view in elevation thereof;

FIG. 5 is a left side view in elevation thereof;

FIG. 6 is a right side view in elevation thereof;

FIG. 7 is a top view thereof; and,

FIG. 8 is a bottom view thereof.

The broken lines represent stitching that forms no part of the claimed design.
